R. A. CARLUCCI.

BANJO.

APPLICATION FILED MAR. 31, 1921.

1,419,818.

Patented June 13, 1922.

UNITED STATES PATENT OFFICE.

ROCCO ANTONIO CARLUCCI, OF WEST NEW YORK, NEW JERSEY.

BANJO.

1,419,818.

Specification of Letters Patent. Patented June 13, 1922.

Application filed March 31, 1921. Serial No. 457,222.

To all whom it may concern:

Be it known that I, ROCCO ANTONIO CARLUCCI, a citizen of West New York, in the county of Hudson and State of New Jersey, have invented a new and Improved Banjo, of which the following is a full, clear, and exact description.

The invention relates to stringed musical instruments and its object is to provide a new and improved banjo arranged to increase the tonal qualities both as to volume and resonance.

Another object is to permit of conveniently and quickly adjusting the neck of the banjo relative to the body with a view to maintain the strings in the desired and correct position relative to the frets on the neck.

With these and other objects in view, the invention consists of certain novel features of construction as hereinafter shown and described and then specifically pointed out in the claims.

A practical embodiment of the invention is represented in the accompanying drawings forming a part of this specification in which similar characters of reference indicate corresponding parts in all the views.

Figure 1 is an inverted plan view of the improved banjo;

Figure 2 is an enlarged sectional side elevation of the same with a portion of the neck and head shown in elevation;

Figure 3 is a face view of the wedge for adjusting the angular position of the neck relative to the body; and

Figure 4 is a sectional side elevation of the same.

The banjo in its general construction comprises a ring-shaped body 10, a neck 11 terminating in a head 12 provided with tuning keys 13 on which wind the ends of the strings 14 stretched over the bridges 15 and 16 and fastened to the tailpiece 17, the bridge 16 resting on top of the parchment or skin head 18 and the bridge 15 being mounted on the outer end of the neck 11. The parchment head 18 extends over a ring 20 held on the top of the body 10, and the parchment head terminates at its edge in a flange 21 engaged by a ring 22 held in place by the usual bolts 23 engaging the bearings 24 attached to the peripheral face of the body 10. The construction so far described is that of an ordinary banjo.

In order to improve the tonal qualities of the banjo use is made of an annular band 25 of sheet material and arranged within the opening of the body 10, the lower edge of the band 25 being seated on an annular shoulder 26 formed on the inner face of the body 10. The band 25 is inclined upwardly and inwardly, and its upper edge engages the under side of the parchment head 18 and projects a distance above the top of the body 10, as plainly shown in Figure 2. By this arrangement the parchment head 18 is stretched over the upper edge of the band 25 and the band forms with the inner surface of the body 10 a resonance chamber 27 closed at the bottom by the band 25 engaging the seat 26 and closed at the top by the portion of the parchment head 18 extending from the ring 20 to the upper edge of the band 25. The band 25 is provided with S-holes 28 for the escape of the sounds from the resonance chamber 27.

In order to fasten the neck in position on the body 10 and to allow of adjusting the neck 11 relative to the strings 14, the following arrangement is provided: The base 30 of the neck 11 is provided with an embedded double nut 31 in which screws the threaded end 32 of a screw rod 33 extending diametrically through the body 10, and the said nut is also engaged by a screw 34 passing through the body 10 adjacent the base 30 of the neck 11. A wedge 35 is introduced between the peripheral face of the body 10 and the base 30 of the neck 11. The thick or base end of the wedge 35 is at the bottom of the body 10 and by moving the wedge 35 up or down the relative angular position between the neck 11 and the body 10 is changed to move the frets 37 of the neck in the desired relation to the strings 14. Thus the frets 37 can be moved nearer to or further from the strings 14 to suit the convenience of the player. Furthermore, the strain exerted by the strings 14 on the neck 11 tends to throw the neck out of alignment with the strings, and by adjusting the wedge 35 the proper relation between the neck and the strings can be established, it being understood that after the wedge 35 has been adjusted the screw rod 33 and the screw 34 are screwed up to quickly fasten the base 30 of the neck 11 to the body 10. The wedge 35 is provided with an elongated

opening 36 for the passage of the screw rod 33 and with a notch 37 for the passage of the screw 34. The wedge is further provided at one face with transversely extending 5 parallel grooves 38 to permit of readily breaking off the portion of the wedge 35 that may project beyond the bottom of the body 10 after the wedge has been adjusted 10 as above explained. The wedge is also provided at the sides with notches 39 which form a hold for adjusting the wedge at the time the screw rod 33 and the screw 34 are loosened, as above explained.

In order to prevent the body 10 from being warped or thrown out of shape on screwing up the screw rod 33 use is made of a tubular brace 40 abutting with its ends against the inner surface of the body 10 at diametrically opposite points thereof and 20 near the bottom of the body, as plainly shown in Figures 1 and 2. The screw rod 33 extends through this tubular brace 40 to hold it in position on the body 10.

Having thus described my invention, I 25 claim as new and desire to secure by Letters Patent:

1. In a banjo, a ring-shaped body, a parchment head held on the said body and an annular resonance chamber within the opening 30 of the said body and having its outer wall formed by the said body, the inner wall of the said resonance chamber being seated on the inner surface of the said body and being inclined upwardly and inwardly and in contact 35 at its upper edge with the under side of the said parchment head a distance inward from the said body, the said inner wall being provided with tone openings.

2. In a banjo, a ring-shaped body, a parchment head held on the said body and an annular resonance chamber within the opening 40 of the said body and having its outer wall formed by the said body, the inner wall of the said resonance chamber being seated on the inner surface of the said body and being inclined upwardly and inwardly and in contact 45 at its upper edge with the under side of the said parchment head a distance inward from the said body, the upper portion of the 50 said inner wall of the resonance chamber projecting above the top of the said body.

3. In a banjo, a ring-shaped body provided at its inner surface with an annular seat, a parchment head attached to the said body 55 and an annular band seated with its lower edge on the said seat and inclined upwardly and inwardly, the upper edge of the band engaging the under side of the parchment head a distance inward and upward from the 60 top of the said body, the said band forming with the said body a resonance chamber

closed at the top by the parchment head, the said band having S-holes.

4. In a banjo, a body, a neck, adjustable means attaching the said neck to the said body, strings stretched over the said body and neck, and an adjustable wedge interposed between and positively and directly engaging the neck and body to adjust the neck relative to the body and the strings and 70 to positively support and maintain the neck in adjusted position with respect to the body.

5. In a banjo, a body, a neck, a screw rod extending approximately diametrically and lengthwise of the head and screwing into 75 the base of the neck to fasten the latter to the body, and a tube through which extends the said screw rod, the ends of the tube butting against the inner surface of the said body at diametrically opposite points. 80

6. In a banjo, a body, a neck, a screw rod extending approximately diametrically and lengthwise of the head and screwing into the base of the neck to fasten the latter to the body, a tube through which extends the 85 said screw rod, the ends of the tube butting against the inner surface of the said body at diametrically opposite points, and a wedge interposed between the base of the said neck and the peripheral face of the said body. 90

7. In a banjo, a ring-shaped body, a neck having a base and a double nut embedded in the said base, a screw rod extending diametrically through the said body and screwing in the said nut, a screw passing through 95 the body and screwing in the said nut, and a wedge interposed between the said base and the peripheral face of the said body.

8. In a banjo, a body, a neck, adjustable means attaching the said neck to the said 100 body, strings stretched over the said body and neck, and a wedge interposed between the said neck and body to adjust the neck relative to the body and the strings, the said wedge having parallel transverse grooves at 105 the base end to permit of breaking off the portion of the wedge projecting beyond the under side of the said body.

9. In a banjo, a body, a neck, adjustable means attaching the said neck to the said 110 body, strings stretched over the said body and neck, and a wedge interposed between the said neck and body to adjust the neck relative to the body and the strings, the said wedge having parallel transverse grooves at 115 the base end to permit of breaking off the portion of the wedge projecting beyond the under side of the said body, the wedge having notches at the sides to provide a hold for adjusting the wedge.

ROCCO ANTONIO CARLUCCI.
